CLAIM

The ornamental design for surgical apparel, as shown and described.

DESCRIPTION

1. Surgical apparel

1.1 : Perspective

1.2 : Front

1.3 : Back

1.4 : Top

1.5 : Bottom

1.6 : Left

1.7 : Referential back view

The evenly-spaced broken lines in the figures form no part of the claimed design; the dashed-dotted broken lines in the figures denote the boundaries of the claimed design and form no part thereof; the right view is omitted as the claimed features depicted in the left view appear symmetrically in the right view.
